UNITED STATES PATENT OFFICE.

CHARLES TOMPSETT, OF OMAHA, NEBRASKA.

COLLAR-FASTENER.

965,668.

Specification of Letters Patent. Patented July 26, 1910.

Application filed July 31, 1909. Serial No. 510,587.

To all whom it may concern:

Be it known that I, CHARLES TOMPSETT, a citizen of the United States, and a resident of Omaha, in the county of Douglas and State of Nebraska, have invented a new and useful Collar-Fastener, of which the following is a full, clear, and exact description.

My invention relates to collar fasteners; my more particular purpose being to provide a flexible, reversible collar fastener, constructed of a single piece of material, comprising a central tongue to secure the collar fastener to the shirt band, and a second tongue integral with the fastener and adapted to securely hold the collar in place and prevent the same from riding the shirt band.

Furthermore, my collar fastener resides in certain novel features of construction, providing comfort and durability, as will be more particularly described hereinafter. Reference is to be had to the accompanying drawings forming a part of this specification, in which like characters of reference indicate corresponding parts in all the views.

Figure 1 shows my improved collar fastener attached to a shirt band and collar, parts of the collar being broken away to show the underlying parts; Fig. 2 is a view similar to Fig. 1, showing the collar removed; Fig. 3 is a sectional view taken on the line 3-3 of Fig. 1; and Fig. 4 is a side elevation of my collar fastener.

Attached to the shirt band A of the shirt B by means of the collar fastener C is a collar D, having therein a tie E. Referring to Fig. 4 of the drawings, the collar fastener C, being preferably made of one piece of material of a flexible nature, consists of a body F having integrally attached thereto a central tongue G, the tongue G being partly separated from the body F by a slit H, approximately shaped like an inverted horseshoe. On the lower part of the body F, directly beneath the tongue G and intermediate the lateral projections I is a larger tongue J, being semi-elliptical in shape and integrally connected with the body F of the collar fastener C.

To affix my collar fastener C to a shirt band A, the said collar fastener C is placed beneath the outer flap A' of the shirt band A, between the flaps A' and A² of the collar band A. The central tongue G of the collar

fastener C is then passed through the button hole A³ of the shirt band A, so that the said tongue G projects through the button-hole A³ and lies on the outer flap A' of the shirt band A. The lower tongue J will then project from between the flaps A' and A², of the shirt band A, and also be below the button-hole A³ of the band A' likewise being below the edge of the said shirt band A. By passing the tongue J through the button-hole D³ of the inner flap D' of the collar D, the tongue J will lie between the said flap D' and the flap D² of the collar D, thereby holding the collar D securely to the shirt band A of the shirt B.

By securing the collar to the shirt band with my collar fastener as mentioned hereinbefore, the collar is prevented absolutely from riding the shirt band. Furthermore the collar fastener being flexible will readily conform to the shape of the neck and form a compact joint, thereby preventing any undue wear and affording great comfort to the wearer.

My collar fastener is reversible, can easily and quickly be put on or taken off, and conforms to the shape of the neck, thereby affording comfort and security and does not tear or wear out button-holes.

Although my collar fastener is preferably made of celluloid, I do not wish to limit myself to this particular material.

Having thus described my invention, I claim as new and desire to secure by Letters Patent:

1. A collar fastener comprising a thin, flat, flexible plate having a tongue centrally disposed in a U-shaped opening in the plate, and a second tongue beneath the first-mentioned tongue, integral with the said plate.

2. A collar fastener comprising a thin, flat, flexible plate having a tongue centrally disposed in the plate in a U-shaped opening in the same, and a second tongue beneath the first-mentioned tongue, the said tongues being adapted to be moved transversely to either side.

In testimony whereof I have signed my name to this specification in the presence of two subscribing witnesses.

CHARLES TOMPSETT.

Witnesses:

ANNA C. KOCARNIK,
GEO. A. MAGNEY.
